WILLIAM J. PLATTEN, OF GREEN BAY, WISCONSIN.

CONCRETE RAIL AND TRACK.

1,339,046.

Specification of Letters Patent.

Patented May 4, 1920.

Application filed December 10, 1919. Serial No. 343,745.

To all whom it may concern:

Be it known that I, WILLIAM J. PLATTEN, a citizen of the United States, and a resident of Green Bay, in the county of Brown 5 and State of Wisconsin, have invented a new and useful Improvement in Concrete Rails and Tracks, of which the following is a full, clear, and exact description.

My invention relates to improvements in 10 a concrete rail and track, and it consists in the combinations, constructions and arrangements herein described and claimed.

An object of my invention is to provide 15 a concrete track which is stronger, more permanent, and cheaper to maintain than the ordinary steel rail and wooden tie track in common use.

A further object of my invention is to provide a rail and track construction which 20 will prevent the usual sagging of the rail.

A further object of my invention is to provide a rail and track construction in which an economy is effected in the use of steel.

25 A further object is to provide a rail and track construction in which the rail is held to the base by means of clamps which are adjustable, and which lock the rail in position, as distinguished from the ordinary 30 means in which a spike is driven into the wooden cross tie, the spike being held by friction.

A further object of my invention is to provide a rail construction in which the 35 rails are positively held from spreading apart.

Other objects and advantages will appear 40 in the following specification, and the novel features of the invention will be particularly pointed out in the appended claims.

45 My invention is illustrated in the accompanying drawings, forming part of this application, in which

Figure 1 is a perspective view of a rail 45 and track construction, forming one embodiment of my invention, and

Fig. 2 is an enlarged sectional view of a modified form of the device.

In carrying out my invention, I provide 50 a sub-base 1, of the shape shown in the drawings, of reinforced concrete, this sub-base being made integral with cross-ties 2 of the same material. The sub-base and cross-ties, are preferably cast in about 8 ft. 55 lengths. Carried by the sub-base are pivoted clamping members 3, like those shown

in Fig. 2, these clamping members being secured at the ends of transverse rods 4 extending through the sub-base.

Arranged to be supported on the sub-base is the rail. This consists of a lower portion 5 of reinforced concrete, having embedded in its upper surface a T-bar 6, as clearly shown in Fig. 1. This T-bar forms the bearing surface of the rail. It will be understood that the central web 7 may be larger than that shown in the drawing without departing from the spirit of the invention. The dimensions of the T-bar would be proportioned in accordance with working conditions. The lower part 5 of the rail thus formed has projecting therefrom bars 8, to which the clamping members 3 are secured, the rail being held to the sub-base by tightening the nuts 9 carried by the clamping members.

In Fig. 2 I have shown a modified form in which the sub-base supports a rail, consisting of the lower portion 5 and the T-bar 6 embedded therein, at its top. The T-bar 80 is made of hard steel, and surmounting it is a softer metal bar 11. A hard steel channel 12 is clamped to the rail by means of bolts 13. This channel, as will be observed, has the section of an inverted U, and constitutes in fact a cap for the metal bar 11 and the T-bar 6, the upper surface of the cap forming the tread of the rail. The channel 12 is replaceable.

In both forms of the device, the line between the sub-base and the lower portion 5 of the rail is approximately the neutral axis of the rail and the sub-base.

From the foregoing description of the various parts of the device, the operation 95 thereof may be readily understood. The design is preferably planned to be equivalent to a 100 lb. standard rail with its accompanying track, under a 19000 lb. wheel load. The rail is designed to be cast in about 26 ft. lengths and in the form shown in Fig. 2 would be laid with expanding joints, these joints being staggered. By casting the track in sections, there would be mutual support for the rail, and sagging could not occur if the road bed happened to be soft under one tie. The sub-base portion of the track has the effect of doubling the effective depth of the rail, giving much greater stiffness and preventing the rail from bending 110 under the load. The sub-base provides a solid junction support for the ends of the

- concrete rails, thereby eliminating the sag usually occurring in present practice where the rail load is at the rail ends borne by one tie. The concrete rail is practically rust proof, as the exposed steel is in the head, where it is self cleaning. The concrete rail would have less than half the steel in the present steel rails. The concrete rail has a lower center of gravity than the steel rail.
- 5 10 Considering the sub-base and the rail as a unit, the neutral axis, as stated, would be along their contacting edges so that very little stress occurs at the junction of the rail and the sub-base, and consequently, there 15 would be no movement between them.
- The form of the device illustrated in Fig. 2 is to be used where the traffic is heavy. The wearing head, *i. e.*, the channel 12, is replaceable at small expense.
- 20 The means for clamping the rail to the sub-base permits the use of standard steel rails on the concrete track with but slight change from the usual construction.

I claim:

- 25 1. A rail and track construction comprising a concrete sub-base, integral cross ties forming a unitary structure with said base, a rail carried by said sub-base, said rail having a lower portion formed of concrete, 30 a metal wearing portion embedded in the concrete at the top thereof, and means for securing said rail to said sub-base.
2. A rail and track construction comprising a concrete sub-base, integral cross ties 35 forming a unitary structure with said base, a rail carried by said sub-base, said rail having a lower portion formed of concrete, a metal wearing portion embedded in the concrete at the top thereof, means for securing said rail to said sub-base, said last 40 named means comprising pivoted clamping members carried by said sub-base, bars car-

ried by the rail and arranged to receive said pivoted members, and nuts for securing said pivoted members to said bars.

45

3. In a rail and track construction, a concrete sub-base, a rail mounted on said sub-base, said rail comprising a lower concrete portion and an upper metal portion partially embedded in said concrete portion, and means for clamping said rail to said sub-base, the neutral axis of said rail and said sub-base, taken as a unit, being the contacting line of the rail with the sub-base.

50

4. A track construction comprising a pair of parallel concrete sub-bases, integral cross ties connecting said sub-bases, and means carried by said sub-bases for securing rails thereto, said means comprising pivoted clamping members carried by said sub-base, bars carried by the rail and arranged to receive said pivoted members, and nuts for securing said pivoted members to said bars.

55

5. A rail construction comprising a lower portion having a flat bottom and tapering sides, and an upper wearing portion comprising a T-bar having its central web extending downwardly, and being embedded in the concrete of the lower portion, the sides of the T-bar being flush with the upper edges of the sides of the sub-base.

60

6. A rail construction comprising a lower portion having a flat bottom and tapering sides, an upper wearing portion comprising a T-bar having its central web extending downwardly, and being embedded in the concrete of the lower portion, the sides of the T-bar being flush with the upper edges of the sides of the sub-base, a relatively soft metal bar surmounting said T-bar, a channel iron cap covering said soft metal bar and said T-bar, and means for securing said cap in position.
